UNITED STATES PATENT OFFICE.

JAMES A. HERRICK, OF NEWARK, NEW JERSEY.

STIRRER FOR GAS-PRODUCERS.

1,077,981.

Specification of Letters Patent. Patented Nov. 11, 1913.

Application filed January 31, 1913. Serial No. 745,328.

To all whom it may concern:

Be it known that I, JAMES A. HERRICK, a citizen of the United States of America, and resident of Newark, in the county of Essex and State of New Jersey, (whose post-office address is 90 West street, New York, N. Y.,) have invented certain new and useful Improvements in Stirrers for Gas-Producers, of which the following is a specification.

10 This invention relates to gas producer apparatus, and has particular reference to the stirring means which may be employed to bring about the proper agitation of the mass within a producer.

15 One of the objects of the invention is to provide in a producer apparatus a poker of novel and useful form, which is particularly effective, which is less liable to breakage than devices of the kind heretofore used, 20 and whose operative position relatively to the producer and to the fuel may be varied as desired.

25 A further object of the invention is to provide a poker of the kind referred to which is readily removable from the producer for substitution or repair.

30 Other objects and aims of the invention, more or less broad than those stated above, together with the advantages inherent, will 35 be in part obvious and in part specifically referred to in the course of the following description of the elements, combinations, arrangements of parts, and applications of principles constituting the invention; and 40 the scope of protection contemplated will appear from the claims.

45 In the accompanying drawings, which are to be taken as a part of this specification, and in which I have shown merely a preferred form of embodiment of my invention, Figure 1 is a sectional view, partly in elevation, showing my invention as applied to a form of gas producer; Fig. 2 is a detail in top plan; Fig. 3 is a detail in section; and Fig. 4 is another sectional detail.

50 Referring to the numerals on the drawings, 1 indicates a section of a producer, which is adapted to be rotated in any usual manner not shown. The numeral 2 indicates the upper section of such producer, held against rotation in any suitable manner, and having a water-sealed connection with the section 1, as shown. The upper section 2 is provided with a cover 3, which carries a 55 fuel hopper 4 and a rotating fuel distributing device 5. Since these parts do not enter into the invention they need not be further

described. The cover portion 3 carries a poker to which this application is particularly directed. In Fig. 1, the cover portion 60 is shown as provided with a plurality of openings, through which pokers such as shown in said figure and in Figs. 3 and 4 may be inserted into the interior of the producer. The poker shown at the left of Fig. 65 1 comprises a trunk 6 which depends from an annular portion 7 which is flanged as indicated at 8 to rest upon the portions of the cover surrounding the openings. 9 and 10 indicate prolongations of this trunk, said 70 prolongations being preferably of different lengths and disposed at different angles to the axis of the trunk. The trunk and its 75 prolongations may be cast in one piece as shown in Fig. 4, or may be made in sections as indicated in Fig. 3. Preferably the poker 80 with its prolongations is of such length that it will extend well down into the lower section 1, so as to be in the most effective position for stirring the fuel within the producer. The trunk and the prolongations being hollow, as shown, water cooling of the 85 poker is readily effected by means of a supply pipe 11 entering through the upper end of the trunk and having branches 12 and 13 90 extending down into the several prolongations 9 and 10, a portion of the water flowing up around these branches and out from the top of the trunk, whence the water finds its way to the depressions 14 in the cover and 95 out through a drain pipe 15. The structure thus far described is useful in itself, the flanges 8 being bolted to the cover, with the legs 9 and 10 extending down into the fuel, so that upon rotation of the lower section 1 95 the poker will serve to agitate the mass. If desired, however, the poker may also be made revolvable. This may be accomplished, as shown in Fig. 1, by providing the trunk 6 with an integral or rigidly attached tubular extension 16 at its upper end which will 100 project above the cover 3 when the poker is in place, to which extension 16 may be secured a gear 17 which may be driven as by means of meshing gears 18 and 19, operated 105 as by means of a crank 20. By these means it is obvious that the poker may be turned as desired within the producer, the flanges 8 being of course not bolted to the cover if the poker is to be revolved. Furthermore, 110 if it be desired to shift the position of the poker laterally with respect to the side wall of the producer, this may be accomplished by removing the gear 17 and replacing it

by a larger or smaller gear, as the case may be, with a corresponding shift of the annular supporting member 7, it being understood that the flanges 8 are of sufficient extent to permit of such changes.

If it be desired to change the vertical relation of the poker with respect to the producer, this may be accomplished as by means of the structure shown at the right of Fig. 10 1 and in Fig. 3. As there shown, the trunk 6 is externally threaded and projects above the cover 3. Coöperating with the threaded end of the trunk is a nut 21, with respect to which the trunk may be rotated to raise 15 or lower it, in an obvious manner, the nut 21 being of course fixed against vertical displacement with respect to the annular supporting member 7 as by means of interengaging portions in the nut and portion 7, 20 indicated at 22, and the supporting member 7 being preferably separate from the trunk 6 and having threaded engagement therewith as shown. By this means, if the wall of the producer should become incrusted, the 25 poker may be moved up and down, so that its field of operation will include the portions of the wall which it is desired to clean, and the lateral approach of the poker to the side wall of the casing 1 may be regulated either by changing the gear 17 so that 30 the poker will be bodily moved with respect to the wall of section 1, or by rotating the poker from handle 20 so that that one of the prolongations 10 will be nearest the wall of section 1 whose angular relation is such that 35 it will approach said wall more closely. Where the poker is to be rotated, as at the left of Fig. 1, and where it is contemplated that various sized gears may be used in 40 place of gear 17, and where consequently the shouldered part 23 of the poker is of smaller diameter than the opening in the cover, it is obvious that some means would need to be provided for keeping the gear 17 45 in mesh with the gear 18. Of course where the shouldered part 23 is of the same diameter as the opening in the cover, the poker may readily be rotated, but the gears cannot be changed.

50 It will be obvious that the invention herein shown and described is capable of numerous modifications. For instance, the supporting part 7 of the poker may be connected to the trunk 6 as by means of a 55 strengthening web 24. Although it is preferred to mount the poker in the cover of the producer, it is quite evident that it might be elsewhere supported, for instance, in the side wall, or upon the twyer box, in 60 which event of course some slight alterations would need to be made in order to adapt the poker to its new location.

As many changes could be made in the above construction, and many apparently widely different embodiments of my invention could be made without departing from the scope thereof, it is intended that all matter contained in the above description or shown in the accompanying drawings shall be interpreted as illustrative and not in a limiting sense. It is also to be understood that the language used in the following claims is intended to cover all the generic and specific features of the invention herein described and all statements of the scope of the invention which, as a matter of language, might be said to fall therebetween.

I claim—

1. A gas producer having a cover portion, and a stirring member depending from the cover portion into the producer, said stirring member being bodily shiftable laterally.

2. A gas producer having a cover portion, and a stirring member depending from the cover into the producer and bodily movable vertically and horizontally with respect to the producer.

3. A gas producer having an opening in its cover portion, and a bifurcated stirring member adapted to be inserted through said opening and having a flanged part to rest upon the cover portion about the opening, said opening in the cover portion being of a size to permit of the bodily withdrawal therethrough of the bifurcated stirring member.

4. A gas producer having an opening in its cover portion, a stirring member bifurcated at one end and having a flanged part intermediate its ends adapted to rest upon the cover portion about the opening, and poker-actuating means detachably connected to the other end of the stirring member.

5. A gas producer having an opening in its cover and a stirring member of such a size that it is insertible and withdrawable through said opening, said stirring member being bifurcated at one end and having intermediate its ends a horizontal flange adapted to rest upon the cover about said opening, said horizontal flange having a depending annular flange and webs joining said depending flange with the stem of said stirring member, the other end of the stirring member beyond the horizontal flange being provided with means for actuating the stirring member.

In witness whereof I have hereunto signed my name in the presence of two witnesses.

JAMES A. HERRICK.
